EXTENSION STEPLADDER

John H. Glower, Chicago, Ill.

Application May 3, 1944, Serial No. 533,962

5 Claims. (Cl. 228—21)

This invention relates to a stepladder and aims to provide a novel means whereby the legs may be extended and the ladder rendered capable of use on a stairway or uneven surfaces, as in plastering, decorating or for ordinary household or other uses.

The more specific objects and advantages will become apparent from a consideration of the description following taken in connection with accompanying drawings illustrating an operative embodiment.

In said drawings—

Figure 1 is a front elevation of the ladder;

Figure 2 is a side elevation thereof;

Figure 3 is a horizontal sectional view taken on the line 3—3 of Figure 2;

Figure 4 is a horizontal sectional view taken on the line 4—4 of Figure 2;

Figure 5 is a vertical sectional view taken on the line 5—5 of Figure 2;

Figure 6 is a view in central vertical section with the extension in adjusted position; and

Figure 7 is a cross sectional view taken on the line 7—7 of Figure 6.

Referring specifically to the drawings, the stepladder has a step section as at 10 comprising side members or stiles 11 bridged by a top step 12 and a series of narrower steps 13, beneath the same, rods or bolts 14, preferably of metal, being used to connect the stiles 11, and to engage directly against the lower surfaces of the steps 13 to reinforce the same.

L-shaped brackets 15 are suitably bolted or otherwise rigidly fastened as at 16 against the under surface of the top step 12 and therethrough V-shaped openings 17 are provided. Said stiles 11 are rigidly connected to the brackets 15 by bolts 18, which bolts serve to rigidly connect bars 19 against the outer sides of the stiles, which bars are provided with V-shaped slots 20 in transverse registry with the slots 17.

A pair of legs 20 are connected together by one or more rungs 21, and the upper ends of the legs have bolts 22 passing therethrough which pivotally and slidably connect the legs in the slots 17, the upper ends of the legs being disposed between the brackets 15 and plates 19.

Between the legs and step section 10, a suitable means is provided to limit relative movement so that the device as thus far described may effectively serve as a stepladder. Such means comprises four links 23 all pivotally connected by a bolt 24 to a roller or tube 25, and being individually pivoted as at 26 to adjacent stiles 11 and legs 20.

Secured against the inner surfaces of the legs 20 and projecting rearwardly beyond the legs, are bars 24, bolts 25, or the equivalent being used to secure them to the legs. Such bars each has a longitudinal slot 26 provided with a series of lateral branches 27 terminating in portions 28 parallel with the slots 26.

An extension section 29 consists of two side bars 30 adapted to slide on the rear surfaces of the legs 20 and overlap the outer sides of the bars 24, such bars 30 being connected by a series of cross elements 31 which may be rungs so as to permit climbing thereon. Said extension 29 also has a transverse rod 32 which is adapted to travel in the slots 26 and into any selected branches 27, so that the extension may be positioned at various adjustments below the lower ends of the legs 20, thus enabling support of the legs and of the step section at different elevations, as on steps 20 or otherwise.

To more securely hold the extension against displacement in its different adjusted positions, hooks or other fastenings 33 are pivoted at 34 to the legs and are engageable with eyelets 35 secured to the bars 30 at various locations.

The adjustment of the upper ends of the legs 20, by means of the bolts 22 and slots 17, enable the legs to be positioned at different distances from the step section 10, as preferred, according to whether the device is used as an ordinary stepladder or with the extension.

Various changes may be resorted to provided they fall within the spirit and scope of the invention.

35 I claim as my invention:

1. A device of the class described comprising a step section, legs pivoted to said section, bars secured to said legs having slots provided with branches, an extension section, and said extension section having a rod extending across the same and movable in said slots and branches to position and secure the extension in adjusted positions.

45 2. A device of the class described comprising a step section, legs pivoted to said section, bars secured to said legs having slots provided with branches, an extension section, said extension section having a rod extending across the same and movable in said slots and branches to position and secure the extension in adjusted positions, and fastenings to secure the extension to the legs against accidental displacement.

50 3. A device of the class described comprising a step section, legs pivoted to said section, bars on the inner surfaces of said legs extending be-

yond their rear surfaces, said bars having slots and branches therethrough beyond said rear surfaces, an extension section having bars in the rear of the legs and on the outer sides of the first mentioned bars, a rod joining the second mentioned bars, said rod being movable in said slots to position the extension at different adjustments.

4. A device of the class described comprising a step section, legs pivoted to said section, bars on the inner surfaces of said legs extending beyond their rear surfaces, said bars having slots and branches therethrough beyond said rear surfaces, an extension section having bars in the rear of the legs and on the outer sides of the first mentioned bars, a rod joining the second mentioned bars, said rod being movable in said slots to position the extension at different adjustments,

and fastenings to secure the extension to the legs against displacement.

5. A device of the class described comprising a step section, legs pivoted to said section, bars on the inner surfaces of said legs extending beyond their rear surfaces, said bars having slots and branches therethrough beyond said rear surfaces, an extension section having bars in the rear of the legs and on the outer sides of the first mentioned bars, a rod joining the second mentioned bars, said rod being movable in said slots to position the extension at different adjustments, and bracket means securing the legs to the step section having V-shaped slots, and said legs having securing elements pivotally and slidably engaged in said slots.

JOHN H. GLOWER.
